MIRROR

Orville B. Solie, Rockford, Ill., assignor to Kroehler Mfg. Co., Naperville, Ill., a corporation of Delaware
Filed Oct. 17, 1968, Ser. No. 14,037

Term of patent 14 years

Int. Cl. D6—01

U.S. Cl. D33—9

FIG. 1

FIG. 2

FIG. 1 is a front elevational view of a mirror showing my new design; and

FIG. 2 is a cross-sectional view thereof, on an enlarged scale, taken substantially on line 2—2 of FIG. 1.

The sides of the mirror and the back thereof are conventionally plain and unornamented.

I claim:

The ornamental design for a mirror, as shown and described.
